UNITED STATES PATENT OFFICE.

HARRY YARRINGTON ARMSTRONG, OF ELGIN, ILLINOIS.

MECHANISM FOR CUTTING WRAPPERS FROM STRIPS,

998,736.

Specification of Letters Patent. Patented July 25, 1911.

Application filed November 10, 1909, Serial No. 527,191. Renewed December 31, 1910. Serial No. 600,230.

To all whom it may concern:

Be it known that I, HARRY Y. ARMSTRONG, a citizen of the United States, and a resident of Elgin, in the county of Kane and State of Illinois, have invented certain new and useful Improvements in Mechanism for Cutting Wrappers from Strips, (Case No. 2;) and I do hereby declare that the following is a full, clear, and exact description thereof, 10 reference being had to the accompanying drawings, and to the letters of reference marked thereon, which form a part of this specification.

This invention relates to improvements in 15 paper feeding and cutting devices for cutting individual wrappers or other short sections from a continuous strip of paper or like material.

The invention is herein shown as designed 20 for use in connection with a wrapping machine for wrapping chewing gum and like thin cakes or sticks of material, such, for instance, as that shown in my prior United States Letters Patent, Number 890,953, 25 granted June 16th, 1908, but may be employed wherever it is desired to cut from a continuous strip a successive series of short sections or wrappers.

Among the objects of the invention is to 30 provide a feeding and cutting mechanism which is exceedingly simple in its construction and efficient and positive in operation, and to otherwise improve devices having the general characteristics herein set forth for 35 the above and other uses.

The invention consists of the matters hereinafter set forth and more particularly pointed out in the appended claims.

As shown in the drawings, Figure 1 is a 40 side elevation of a wrapper feeding and cutting mechanism embodying my invention. Fig. 2 is a vertical section thereof. Fig. 3 is a front elevation of the mechanism, looking in the direction of the arrow, on line 3—3 of Fig. 1. Figs. 4 and 5 are perspective views of the cutting knives. Fig. 6 is a detail horizontal section on the line 6—6 of Fig. 1.

As shown in the drawings, 10 designates a 50 hopper from the bottom of which the pieces of gum are fed by gravity into a suitable horizontal way 11 by means of a plunger 12, which reciprocates through said way, and 13 designates a recess below said way into 55 which wrappers are dropped by the wrapper cutting mechanism so that they will stand

across the path of the gums so as to be folded thereabout as the gums are directed toward the wrapping mechanism.

The mechanism constituting the present 60 invention is located above the wrapper recess and operates to cut from the lower end of a continuous strip *a* the wrappers and to discharge them into said recess, the strip being intermittently fed or advanced to the 65 cutting means as the wrappers are severed from the strip.

Referring now to the particular form of cutting and delivering mechanism herein shown, said parts are made as follows: 14, 70 15 designate the principal parts of the frame of the machine, the former being fixed and the other movable toward and from the same. The cutting and feeding devices are carried by these frames, and they are hereinafter termed the fixed and movable jaws. They comprise end members 16, 17, respectively, the end members of each frame being connected by connecting bars or webs 18, 19. The lower ends of the end members 80 16, 16 are provided with base supports 20 which are attached in any suitable manner to the main frame 21 of the machine proper, and said supports also carry the bearings 75 for certain of the feed roller shafts, as will 85 hereinafter more fully appear. The swinging or movable jaw 15 is pivoted at its upper end by means of a pivot rod or pin 22 to the upper end of the fixed or stationary jaw, the said jaws being provided with inwardly 90 extending overlapping lugs 23, 24 which are apertured to receive the pivot rod or pin. The said stationary and movable jaws carry 95 at their lower ends cutting knives 25, 26, respectively, the cutting edges 27, 28 of which co-operate with each other with a shearing engagement. The fixed knife 25 extends between the end members of the fixed jaw and is secured at its ends to the undersides of inwardly extending lugs 29 of 100 the end members of said fixed jaw by means of screws 30 extending upwardly through said fixed knife and said lugs. Said knife is provided with slots 31, 31 through which 105 extend the screws 30, whereby the stationary knife may be adjusted toward and from the movable knife as may be required by reason of the wear on the knives in action. The knife 26 is carried by the movable jaw in a manner hereinafter to be described. Located above said knives, and carried by said 110 jaws, are strip feed rollers 35, 36, respec-

tively, between which is fed the strip *a* from which the wrappers or other sections are cut. The rollers are fixed to shafts 38, 39, respectively, which extend transversely across the fixed and movable jaws and are mounted in bearings carried by the end members of said jaws. Said shafts are provided at their ends, at one side of the machine, with meshing pinions 40, 41 by which one shaft 10 is driven from the other, and one of the shafts, the shaft 38 as herein shown, may be driven in any suitable manner from the machine, as for instance, through the medium of a pulley 42. Located below the cutting knives, between the same and the wrapper receiving recess 14, are parallel co-acting wrapper delivery rollers 43, 44 that are fixed to shafts 45, 46 which extend transversely across the machine and are relatively mounted in bearings carried by the supporting base 20 of the fixed jaw. One of the shafts, the shaft 46 as herein shown, is adapted to be driven from the shaft 38 of the strip feeding rollers by means of meshing gear wheels 48, 49 fixed to the shafts 38 and 46 respectively. The shaft 45 is driven from the shaft 46 by intermeshing pinions 46' fixed to said shafts at one side of the mechanism.

30 The means of mounting the movable knife 26 on the swinging jaw are made as follows: The said movable knife 26 is supported from the shaft 39 of the roller 36 of the swinging jaw through the medium of hangers 50, 50, one located at each side of the mechanism. Said hangers are pivotally carried by the shaft 39 and are provided at their lower ends with inwardly extending studs 51, 51 which enter pivot apertures 52, 52 in the ends of the movable knife. The shearing edge of the movable cutting knife, thus pivoted to the hangers 50, is held up against guide arms 54, 54 at the ends of the stationary or fixed knife by means of spring-held links 56, 56 which are pivoted at their lower ends to oppositely extending lugs 57 at the ends of the movable knife, between the pivot apertures 52 and the cutting edge of the knife. The said links are connected at 50 their upper ends, through the medium of contractile springs 58, 58 with eye-bolts 59, 59 which extend upwardly through lugs 60 at the pivoted end of the movable jaw and through adjusting nuts 61 lying on said lugs. 55 The said links 56 are curved to pass around the strip feeding roller 36.

60 The provision of the guide arms 54, 54 at the ends of the stationary knife, which extends inwardly toward the movable knife, and against the under sides of which the movable knife is yieldingly held and by which it is guided, affords means by which the cutting edges of the knives are maintained in proper cutting relation when the 65 movable knife is swung toward and from

the fixed knife and also affords means for providing between said knives, when the movable knife is swung away from the stationary knife, a space through which the strip *a* may pass when said strip is being fed downwardly by the feeding rollers 35, 36, the said guide arms 54 constituting the end boundaries of said space.

A feature of my invention resides in the provision of means for swinging the movable jaw toward and from the stationary jaw to actuate the cutting knives in timed relation to the feeding movement of the strip *a* from which the wrappers are cut, so arranged that the feeding movement of the strip occurs when the knives are separated and is arrested when the knives are brought together in cutting relation; the intermittent feeding movement of the strip and the cutting of the wrappers from the lower end thereof being alternately effected. The construction herein shown for effecting this result is made as follows: One of the strip feeding rollers, to wit, the roller 36, as herein shown, is eccentric with respect to the axis of rotation of its shaft 39, while the other roller 35 is eccentric. The pinion 41 of the shaft of the eccentric roller is likewise eccentric and is arranged with its eccentric portion on the same side of the shaft 39 as the eccentric portion of the roller. When the highest portion of the pinion 41 meshes with the mating pinion 40, therefore, the lower end of the swinging jaw will be moved outwardly and the cutting knives will be separated from each other as shown in Fig. 1, so that at this time the strip of paper is free to pass between the cutting edges of the knives. The highest portion of the eccentric strip feed roller 36 is at this time between its shaft and the mating roller 35 so as to coact with the latter roller to feed or advance the strip between said rollers when the knives are so separated, as will be apparent from an inspection of Figs. 1 and 2. When the lowest part of the eccentric pinion meshes with its mating pinion the swinging jaw is moved inwardly, under the force of a suitable actuating device, as a spring or weight, and when said jaw swings inwardly the movable knife co-operates with the stationary knife to cut from the strip of paper a length or section that has been fed downwardly between the cutting knives at the time the highest part of the roller 36 co-operates with the roller 35. In order to interrupt the feed of the strip at the time the knives are co-operating to cut a section or wrapper therefrom, the said eccentric feed roller is lowered or depressed in a part of its circumference, as indicated at 36'. The engagement of the teeth of the lower portion of the pinion 41 limits the inward movement of the jaws and the roller 36 so as to leave the roller 36 at this time clear of the roller 130

35, whereby during the cutting action of the knives no advance of the strip will occur. The higher portion 36^a of said feed roller 36 is made of a length equal to the length of the 5 wrapper or section to be cut from the strip, so that in each rotation of the roller 36 a length of the strip will be fed downwardly equal to the length of the wrapper or section to be cut from the strip. Thereafter the 10 lower portion 36' of the roller 36 is brought opposite to the companion roller 35 and is arrested short of contact therewith, through the action of the teeth of the driving pinions of said rollers, whereupon the feeding movement of the strip is arrested during the cutting action of the knives.

The means shown for holding the feed roller pinions pressed together and which also co-operates with the lower portion of 20 the pinion 41 to move the knives into cutting relation, and permits the knives to separate when the highest portion of the pinion 41 is engaged with its mating pinion, are made as follows: 70, 70 designate two horizontal rods located one at each side of the mechanism and extending from front to rear thereof through lugs 71, 71 projecting laterally from the end members of the jaws. Said rods are each provided at one end with 30 a head 72 which heads engage the lugs 71 of one jaw and the rods have sliding engagement with the lugs 71 of the other jaw. Interposed between the latter lugs and screw-threaded nuts, or other suitable heads 73 at 35 the outer screw-threaded ends of the rods 70, are spiral expansively acting springs 74, 74. These springs, as it will be obvious, tend to press or force the jaws together to bring the knives in cutting relation, and to hold 40 the strip roller pinions engaged with each other, and yield to permit the movable jaw and the knife carried thereby to be swung rearwardly when the highest portion of the pinion 41 engages with the mating pinion 40.

45 In order to guide the strip downwardly to the space between the knives and to prevent the strip from clinging or adhering to the strip feed rollers, I have provided guiding and clearing wires 75, 76 the latter of 50 which are fixed in and extended downwardly from a bar 77 that extends across and connects the end members of the stationary jaw, and the former of which are fixed to a rocking bar 78 that is mounted 55 at its ends in notched lugs 79 extending rearwardly from said bar 77. The said rocking bar 78 is held from rising in said notched lugs 79 by means of screws 80 extending transversely through the upper ends of the 60 notches above said bar 78. The wires 76 extend upwardly through vertical openings in the bar 77 and are held therein in any suitable manner, as for instance, by the set screws 81 extending through screw-threaded 65 openings in said bar and impinging at their

inner ends against the upper ends of said clearance wires. The lower ends of the clearance wires are arranged generally parallel with each other on opposite sides of the path of the strip *a* and occupy grooves 84, 76 85 in the strip feed rollers.

In the operation of the mechanism thus described, the strip feed rollers and the lower wrapper feed rollers are continuously rotated and the strip, which is unwound 76 from a roll of paper (not shown) suitably supported above the cutting mechanism, is fed between the upper feed rollers downwardly into the space between the knives at the time the highest portion of the eccentric 80 roller 36 coacts with the companion roller 35. At this time the highest portion of the pinion 41 is coacting with its mating pinion 40 to hold the cutting knives separated so as to permit the strip to pass freely through 85 the space between the knives. As the highest portion of the eccentric pinion 41 leaves its mating pinion, the springs 74, or other equivalent devices, swing the movable jaw inwardly to bring the knives into cutting 90 relation with each other, and just before the knives are brought into cutting relation the clearance depression 36' of the roller 36 is brought opposite to its mating roller 35 so as to afford a space between the rollers 95 and thus release the strip from the gripping action of the rollers and arrest its feed during the cutting operation. After the wrapper or section has been cut from the strip the knives are again separated, through 100 the action of the eccentric pinion, and the rollers are thereupon brought into gripping action upon the paper strip to again advance the strip a distance equal to the length of a wrapper or section to be cut therefrom, 105 after which the knives are brought into action to cut a new wrapper or section from the strip. This operation continues to effect the alternate feed of the strip and the cutting of the wrappers or sections therefrom 110 as long as the mechanism continues in operation.

It will be understood that the structural details of the feed and cutting mechanism are capable of variation within the spirit and scope of the invention, and the invention is not limited to such details except as hereinafter made the subject of specific claims.

I claim as my invention:

1. Mechanism for feeding a strip and cutting sections from the advance end thereof, comprising feeding means, cutting means, members movable relatively toward each other and carrying the co-operative parts of 115 the feeding means and the cutting means and adapted by such relative movement to bring the feeding and cutting means into and out of operative position, and means for actuating said members.

2. Mechanism for feeding a strip and cutting sections from the advance end thereof, comprising jaws movable one toward and from each other, feeding means carried by 5 said jaws, cutting means carried also by said jaws and means for imparting relative movement to the jaws.
3. Mechanism for feeding a strip and cutting sections from the advance end thereof, 10 comprising a fixed and a movable jaw, co-operating knives carried by said movable jaw, feed rollers carried one by each jaw and means for moving said jaws toward and from the fixed jaw.
- 15 4. Mechanism for feeding a strip and cutting sections from the advance end thereof, comprising a fixed and a movable jaw, co-operating knives carried by said jaws, feed rollers carried one by each jaw, and intermeshing pinions on the shafts of said feed rollers, one of said pinions being an eccentric pinion.
5. Mechanism for feeding a strip and cutting sections from the advance end thereof, 25 comprising a fixed and a movable jaw, co-operating knives carried by said jaws, strip feeding means carried by said jaws embracing an eccentric roller carried by one of said jaws, and an eccentric pinion fixed to the 30 shaft of said eccentric roller for rotating the same and for controlling the cutting movement of said knives.
6. Mechanism for feeding a strip and cutting sections from the advance end thereof, 35 comprising a fixed and a movable jaw, co-operating knives carried by said jaws, strip feeding means carried by said jaws embracing an eccentric roller carried by one of said jaws, and an eccentric pinion fixed to the 40 shaft of said eccentric roller for rotating the same and for controlling the cutting movement of said knives, said eccentric roller being provided throughout a portion of its circumference with a clearance depression 45 for the purpose set forth.
7. Mechanism for feeding a strip and cutting sections from the advance end thereof, comprising a fixed and a movable jaw, co-operating knives carried by said jaws, strip 50 feeding means carried by said jaws embracing an eccentric roller carried by one of said jaws, an eccentric pinion fixed to the shaft of said eccentric roller for rotating the same and for moving one of the knives away from 55 the other and a spring acting in opposition to the eccentric pinion for moving the movable knife into cutting relation to the other knife.
8. Mechanism for feeding a strip and cutting sections from the advance end thereof, 60 comprising two feed rollers between which the strip is fed and fixed to shafts movable one toward and from the other, intermeshing pinions fixed to the shafts of said rollers 65 one of which is an eccentric pinion, and cutting means controlled by said eccentric pinion.
9. Mechanism for feeding a strip and cutting sections from the advance end thereof, 70 comprising a fixed and a movable jaw, two feed rollers between which the strip is fed and fixed to shafts, one of which is rotatively mounted in the fixed jaw and the other in the swinging jaw, one of said feed rollers being eccentric, and pinions on the 75 shafts of said rollers one of which is eccentric, and cutting knives one of which is mounted on the fixed jaw and the other of which is carried by the movable jaw.
10. Mechanism for feeding a strip and 80 cutting sections from the advance end thereof, comprising a fixed and a movable jaw, two feed rollers between which the strip is fed and fixed to shafts, one of which is rotatively mounted in the fixed jaw and the 85 other in the swinging jaw, one of said feed rollers being eccentric, pinions on the shafts of said rollers one of which is eccentric, and cutting knives one of which is mounted on the fixed jaw and the other of which is carried by the movable jaw, and a spring tending 90 to press said jaws together.
11. Mechanism for feeding a strip and cutting sections from the advance end thereof, 95 comprising a fixed and a movable jaw, two feed rollers between which the strip is fed and fixed to shafts which are rotatively mounted in said jaws, intermeshing pinions on said shafts, one of said feed rollers being eccentric and the pinion on the shaft of said latter roller being also eccentric and cutting knives one of which is mounted on the fixed 100 jaw and the other of which is carried by the movable jaw, one of said feed rollers being provided in its circumference with a clearance depression for the purpose set forth.
12. Mechanism for feeding a strip and cutting sections from the advance end thereof, 105 comprising a fixed and a movable jaw, co-operating strip feed rollers carried one by each jaw between which the strip is fed, means for rotating said rollers arranged to control the movement of the jaws toward and from each other, a knife carried by the fixed jaw below said rollers and a co-operating knife pivoted to the movable jaw and having means for holding it yieldingly 115 pressed against the fixed knife.
13. Mechanism for feeding a strip and cutting sections from the advance end thereof, 120 comprising a fixed and a movable jaw, co-operating strip feed rollers carried one by each jaw between which the strip is fed, means for rotating said rollers arranged to control the movement of the jaws toward and from each other, a knife carried by the fixed jaw below said rollers, a co-operating knife pivoted at its ends to the movable jaw and spring pressed links pivoted to the ends 125 of the movable knife between its cutting 130

edge and its pivotal connection with the movable jaw for holding the movable knife yieldingly pressed against the fixed knife.

14. Mechanism for feeding a strip and
5 cutting sections from the advance end thereof, comprising a fixed and a swinging jaw, coöoperating strip feed rollers carried one by each jaw and between which the strip is fed, a knife carried by said fixed jaw below
10 the rollers, and a coacting knife carried by the movable jaw, one of said knives be-

ing provided at its ends with arms which extend toward the other knife and upwardly against which the latter knife is spring held. 15

In testimony, that I claim the foregoing as my invention I affix my signature in the presence of two witnesses.
